COOK C. LAWRENCE AND JAMES LEWIS, OF MARENGO, MICHIGAN.

Letters Patent No. 97,301, dated November 30, 1869.

IMPROVED REST FOR CARRIAGE-TOPS.

The Schedule referred to in these Letters Patent and making part of the same.

To all whom it may concern:

Be it known that we, COOK C. LAWRENCE and JAMES LEWIS, both of Marengo, in the county of Calhoun, and State of Michigan, have invented a new and useful Improvement in Carriage-Top Rests, or Props; and we do hereby declare that the following is a full, clear, and exact description of the same, reference being had to the annexed drawings, forming a part of this specification, in which—

Figure 1 exhibits our bracket-rest, in perspective, as usually made for heavy tops.

Figure 2 exhibits, also in perspective, a modified form, which may be used for very light tops.

Similar letters of reference indicate corresponding parts in both figures.

Our invention relates to an improvement in the manner of supporting and steadyng the tops of carriages when let down, and consists in the employment of an adjustable bracket, or hub, furnished with a concave seat, and arranged, in relation with the back carriage-top bows, to support and keep the top, when let down, in place, in a manner that we will now proceed to describe, for the purpose of enabling others skilled in this art to properly construct the same.

A represents the broken-off curved corner of a carriage-seat rail, furnished with the usual branch prop-iron B, nutted at the end to secure the foot of the main joint-brace C, pivoted thereon. (See dotted lines.)

In the ordinary mode of construction, a spool, covered with leather or other trimming material, is placed on this prop-iron, so as to fill the space between the brace and seat-rail, on which covered spool the top, when let down, is supported, by means of the hinder bows resting thereon.

There are many disadvantages attending this arrangement. In the first place, the said bow-prop irons, and the bow slat irons in front of the seat, are so near together, as compared with the overhang of the top, that when the top is suddenly let down, it acts like the long weighted arm of a lever, the prop being the fulcrum, and either breaks the hind bows at the point of impact, or breaks some of the connecting-irons. In addition, no provision is made for the lateral displacement and bobbing up and down of the top, when driving over a rough road with the top down.

To remedy these defects, we secure on each of the prop-irons B, in the place of the usual covered spool, an arm or bracket-rest, D, the supporting end of which will project sufficiently behind the carriage-seat.

We usually construct these arm-rests in malleable cast-iron, and cast in a suitable eye to fit the prop-iron, as shown. A set-bolt, F, secures them in place.

The projecting ends of the arm-rests are provided with light concave-shell seats, as seen at d, and we find it convenient to form the sides with flaring side-lips l, to guide the hind carriage-top bows into place, and to slot, or otherwise perforate the shell-seat to lighten the same, and allow the ready escape of mud-splashings.

The top bows may be readily held secure in their concave seats, when lowered, so as to prevent the carriage-top from lifting, or swaying from side to side, either by making the concavity of the shell-seat wedge-like, to nip the bows when inserted, or by leather or other elastic bands, not shown, properly secured to the bows, so that when lowered, said bands may be slipped over the concave seats d, and hold said bows firmly down in place; and it will materially aid in keeping the bands from slipping, if the under side of the seat-shell is corrugated, as seen at i.

The position of the top bows, when lowered, is indicated by the dotted lines.

Fig. 2 illustrates a modified form of the rest, in which the shell concave seat extends the whole distance of the arm, and forms, in fact, the arm or bracket, itself.

We have already enumerated all the defects of the old system, except, perhaps, the wear and tear occasioned by the lateral freedom to sway back and forth.

In our arrangement, the overhang of the carriage-top being reduced, the impact of a sudden fall is not sensibly felt, and the top bows being secured in concave seat-rests, there can be no lateral displacement to produce the strain, breakage, and wear, which result in the ordinary mode of supporting carriage-tops when lowered.

We are aware that a device somewhat resembling that shown in fig. 2, of our drawings, has been made, but it has not the concave seat or flaring sides, and is not adjustable. To this device we lay no claim; but having thus described our invention,

What we claim, and desire to secure by Letters Patent, is this:

The arm-rests D, furnished with concave seats d, and flaring side, l, when constructed and arranged substantially as shown and described, and adjustably fitted on the prop-irons B of a shifting or stationary carriage-seat rail, substantially as and for the purpose set forth.

COOK C. LAWRENCE.
JAMES LEWIS.
